UNITED STATES PATENT OFFICE

166,206

STAPLE DRIVER OR SIMILAR ARTICLE

Herbert W. Marano, Brooklyn, N. Y., assignor to
Wilson-Jones Company, Chicago, Ill., a corpora-
tion of Massachusetts

Application January 30, 1951, Serial No. 14,038

Term of patent 14 years

(Cl. D74—1)

To all whom it may concern:

Be it known that I, Herbert W. Marano, a citizen of the United States and a resident of Brooklyn, New York, have invented a new, original, and ornamental Design for a Staple Driver or Similar Article, of which the following is a specification, reference being had to the accompanying drawing, forming a part hereof, in which

Figure 1 is a side elevational view of a staple driver or similar article, showing my new design;

Figure 2 is a top plan view thereof;

Figure 3 is a bottom plan view thereof;

Figure 4 is a front end elevational view thereof; and

Figure 5 is a rear end elevational view thereof.

The dominant feature of the design resides in

the particular shape and appearance of the lower jaw of the staple driver, as seen most clearly in Figure 1.

I claim:

The ornamental design for a staple driver or similar article, as shown and described.

HERBERT W. MARANO.
